UNITED STATES PATENT OFFICE

JOHN T. KERSHAW, OF HAVERHILL, MASSACHUSETTS, ASSIGNOR TO UNITED SHOE MACHINERY CORPORATION, OF PATERSON, NEW JERSEY, A CORPORATION OF NEW JERSEY

METHOD OF MAKING COVERED HEELS

Original application filed August 31, 1927, Serial No. 216,682. Divided and this application filed April 18, 1929. Serial No. 356,214.

The present invention relates to improvements in the art of making covered heels for shoes. As herein illustrated the invention is concerned particularly with methods of preparing the breasts of heels for the reception of paneled breast coverings, the present application being a division of a copending application, Serial No. 216,682, filed August 31, 1927, in the name of the present inventor.

10 In the application just referred to, and also in United States Letters Patent No. 1,691,149, granted Nov. 13, 1928, upon application of Anthony Cocoza, there is disclosed an improved heel having in its breast surface a shallow recess extending from the top to the bottom of the breast formed between relatively narrow ribs which extend along the opposite lateral margins of the breast and having a paneled breast covering comprising a panel portion which is received in the recess and frame portions which overlie the ribs of the heel breast. On account of the peculiarities in the shapes of the breasts of heels, and more particularly of Louis heels, and because of the necessity of careful work in order to produce the necessary degree of perfection in the finished heels, the operation of recessing the breasts of heels has heretofore required a high degree of skill on the part of the workman.

20 and accordingly the recessing operation has been an expensive one, adding materially to the cost of making and covering the heels.

In view of the foregoing, one object of the present invention is to reduce, so far as practicable, the expense of heel breast preparing or recessing operations such, for example, as those above referred to.

To this end, the present invention provides a method which consists in forming a groove along each lateral margin of the breast of a heel to define the lateral edges of a recess and thereafter widening the grooves in directions toward the middle of the heel breast. As herein illustrated the above-mentioned steps of forming and widening the grooves do not result in the formation of a recess having a bottom surface of the ultimate shape desired and a third step is also practised which consists in removing material adjacent to the inner sides of the widened grooves to produce a

recess having a bottom surface of the desired contour. As illustrated, also, the marginal grooves in the heel breast are formed separately and each groove is cut to the same predetermined depth and furthermore each groove is made parallel to and is spaced a predetermined distance from the adjacent lateral edge of the heel breast. This is accomplished by moving the heel relatively to a grooving tool while guiding the heel by holding those portions of its breast and side surfaces immediately adjacent to one of its lateral edges against suitably positioned gage members.

The invention will be explained with reference to the accompanying drawings, in which

Fig. 1 is a view in front elevation, of one form of apparatus for use in recessing heel breasts in accordance with the present invention;

Fig. 2 is a detailed view, on an enlarged scale, of one of the cutters for performing the first stage in the recessing operation, illustrating the mode of operation of the cutter upon a heel, and also showing the work gages associated with the cutter;

Fig. 3 is a fragmentary cross-sectional view of a heel in process of being operated upon by the groove-forming cutter shown in Fig. 2;

Fig. 4 is a detailed view of one of the cutters for performing the second stage of the recessing operation, illustrating its mode of operation upon a heel;

Fig. 5 is a view, in end elevation, of the cutter shown in Fig. 4;

Fig. 6 is a cross-sectional view of a heel illustrating the appearance of the breast face of the heel after the second stage of the recessing operation has been completed;

Fig. 7 is a detail view of the cutter for performing the third stage of the recessing operation, illustrating its mode of operation upon the heel;

Fig. 8 is a cross-sectional view on the line VIII—VIII of Fig. 7;

Fig. 9 is a perspective view of an uncovered Louis heel having a recessed breast;

Fig. 10 is a detailed view of a modified form of groove-forming cutter and associated work gages; and

Fig. 11 is a detailed view showing a modification of the cutter for removing material from between the marginal grooves in the breast of a heel.

Referring to Fig. 1 of the drawings, the apparatus therein shown comprises mechanism A for performing the first step or stage in the operation of recessing the breast of a heel, viz., grooving the opposite lateral margins thereof, and mechanisms B and C for performing the two succeeding stages of the recessing operation, viz., widening the marginal grooves formed by the mechanism A, and removing the projection in the middle of the heel breast resulting from the operation of the groove-widening mechanism B.

The grooves-forming mechanism A comprises twin heads 12, 12 mounted at opposite sides of a frame or standard 14 secured to a bench 16. The two heads 12 are provided with rotary cutters and work gages designed to operate separately upon the opposite lateral margins of a heel breast and, as the parts carried by each head are duplicates of those carried by the other, a description of one set of parts will suffice for both. The head 12, which in Fig. 1 is located on the left-hand side of the standard 14, is formed with spaced bearings 18, 18 for a vertical spindle 20. The spindle 20 is provided, between the bearings 18, with fast and loose pulleys 22, 24 adapted to be driven by a belt (not shown) connected with a suitable source of power. At its lower end the spindle 20 carries a groove-forming tool 26 in the form of an end milling cutter. As best shown in Figs. 2 and 3, the tool 26 is formed with both sides and end cutting teeth and the tool is shaped to make a V-shaped cut in the work, such as that shown at 28 in Figs. 2, 3 and 4. The work is positioned relatively to the cutter 26 by means of suitably arranged work gaging and guiding devices so that one side of the V-shaped cut may be disposed substantially at right angles to the breast of the heel to constitute one of the edges of the recess to be formed therein while the other side of the V-shaped cut slopes toward the middle of the breast of the heel.

The work gaging and guiding devices comprise a gage roll 30 (Fig. 2), carried by an angularly disposed fixed arm 32, and a surface or shoulder 34 which is formed at the free extremity of the arm 32 and is disposed at a substantial angle (illustrated as something more than 90°) to the portion of the gage roll 30 that contacts with the work. The arm 32 is fixedly but adjustably secured, by means of a set screw 36, to the lower end of a post 38 which is disposed at right angles to the arm and is adjustably but fixedly secured, by means of a set screw 40, to a bracket 42 secured to the head 12. By loosening the set screws 36 and 40 and suitably adjusting the post 38 and the arm 32, the gages 30 and 34 may be adjusted relatively to the grooving

tool 26 to vary the depth of the groove or the distance between the groove and the edge of the heel breast or both said measurements as may be desired.

The mechanism B comprises a frame 44 secured to the bench 16 and provided with alined bearings 46 for a horizontal spindle 48 adapted to be driven by a belt 50 arranged to pass over fast and loose pulleys 52 and 54 on the spindle 48. The opposite ends of the spindle 48 extend beyond the bearings 46 and at each end of the spindle there is secured a tool 56 (see also Fig. 4) for widening the V-shaped groove formed in the heel-breast margin by the cutter 28. As shown, the tool 56 is in the form of a milling cutter of frusto-conical shape adapted to widen or reform one of the marginal grooves 28 from the width and shape shown in Fig. 3 to the width and shape shown at 58 in Fig. 6. In order to insure that the inner edges of the teeth of the cutter 56 shall not engage the perpendicular shoulder that forms the outer side of the marginal groove, and to assist in guiding the heel as it is manually presented to the action of the cutter 56, a guard 60, in the form of an annular flange, is formed at the outer end of a sleeve 62 which is loosely mounted upon a reduced portion of the spindle 48 between the cutter 56 and an annular shoulder 64 on the spindle.

The mechanism C comprises a frame, of the same shape as the frame 44, which is secured to the bench 16 and is provided with alined bearings for a horizontal spindle 68. The spindle 68 is provided with fast and loose pulleys 69, 70 arranged to receive a belt 71 by means of which the spindle is driven. One end of the spindle 68 projects outwardly beyond the frame and to this projecting end there is secured a tool for finishing the recessing operation, this tool being in the form of a cylindrical milling cutter, best shown at 72 in Fig. 7. To guard against injury to the opposite lateral edges of the recess in the heel breast by the teeth of the cutter 72, guard flanges 73, 73 are formed at the inner ends of sleeves 74, 74 which are loosely mounted upon the spindle 68 at opposite sides of the cutter and are frictionally held in place by means of springs 76, 76 surrounding the spindle between the outer ends of the sleeves 74 and annular shoulders 78 and 80 formed on the spindle.

In accordance with the present invention a heel, the breast of which is to be recessed, is presented manually, first to the cutter 26 at one side of the mechanism A to form a groove along one lateral margin of the heel breast, and thereafter to the cutter at the opposite side of the mechanism A to form a groove along the other lateral margin of the heel breast. Preferably, the heel is introduced, top-lift end first, into the field of operation of the cutter, the heel being held by the op-

erator in the inclined position shown in Fig. 2 with the corner at the upper lateral edge of the heel breast located in the angle between the surfaces of the gages 30 and 34. The heel is moved backwardly away from the operator and against the cutting tool 26, causing the latter to operate progressively along the margin of the heel to form a V-shaped groove therein, the operator manually supporting the heel against the thrust of the cutting tool, while manipulating it as is necessary to hold it continuously against both gages. Preferably the heel will be held with its breast face transversely disposed relatively to the cutter at such an angle as to cause the outer side of the V-shaped groove to be substantially perpendicular to the surface of the breast, but if desired this angular position of the heel may be varied so that the outer side of the groove will be either undercut or beveled in the opposite direction. After a groove has been formed along one margin of the breast of the heel the heel is presented to the cutter at the opposite side of the mechanism A and manipulated in a manner similar to that already described so that a V-shaped groove similar to the first is formed along the other lateral margin of the breast, the grooves then appearing as shown in Fig. 3 with their outer side walls defining edge faces which are to constitute the opposite edges of the recess in the breast.

It is then necessary to remove the material between the V-shaped grooves 28 to a depth equal to the height of the outer walls of the grooves. To this end, the grooved heel is next presented first to the mechanism B and then to the mechanism C to remove the material in two successive stages. The first stage consists in widening first one groove and then the other to substantially half the width of the recess to be produced, while the second stage consists in removing the remainder of the material necessary to produce a recess of uniform depth in the heel breast. As illustrated the material to be removed at this second stage is in the form of an angular ridge 84 (Fig. 6) left as a result of the first stage of the operation. In performing the first stage of operations after the forming of the grooves, the grooved heel is presented first to one of the cutters 56 of the mechanism B for the widening of one of the grooves 28 and next to the other cutter 56 for the widening of the other groove 28. The cutters 56 being of frusto-conical form, as shown, operate to widen the grooves by cutting away or reforming the inner sloping sides of the grooves so as materially to lessen the pitch of these sides. In Fig. 4, one of the cutters 56 is shown in the operation of widening one of the grooves 28. As also shown in Fig. 4, the breast face of the heel is presented preferably with its upper or wider end foremost. In this figure the portion of the groove 28 which

appears below or in front of the cutter 56 has not been acted upon thereby but the portion 80 which appears above and to the rear of the cutter 56 shows plainly how the relatively narrow groove 28 has been reformed and widened by the action of the cutter. The dotted lines shown at 82 indicate the outline of the material, extending from the bottom of the groove 28 to the middle of the heel breast, which has been removed by the cutter. After the two cutters 56 have operated upon opposite sides of the breast of the heel the latter appears in cross-section as shown in Fig. 6.

The next operation consists in removing the angular ridge or projection 84 (Fig. 6) so that the covering to be laid against the breast face of the heel will lie flush with the ribs of the opposite sides of the breast. This projection 84 of the heel breast is removed by presenting it to the action of the cutter 72, as clearly illustrated in Fig. 7. During the operation of the cutter 72 the guard flanges 73 at opposite ends of the cutter protect the shoulders formed at the outer sides of the grooves from being injured. After the cutter 72 has completed this operation upon a heel the latter appears as shown in Fig. 9 wherein the recess is indicated at 86, the depth of the recess being uniform throughout its width and the opposite edges of the recess being defined by shoulders 88 which are parallel to the adjacent lateral edges of the heel breast.

In accordance with a modification of the above-described method, the grooves in the breast, instead of being V-shaped in cross-section, as above described, may be formed with parallel sides, as shown in Figs. 10 and 11. To produce grooves of this form an end milling cutter, such as that indicated at 90 in Fig. 10, may be employed. As also shown in Fig. 10, a modified arrangement of work gages is provided, there being shown a stationary gage 92 for engaging the side of a heel substantially at the breast corner to locate the groove transversely of the breast, and a stationary gage 94 for engaging the edge of the breast surface to determine the depth of the groove. The gage 94 is preferably apertured, as shown at 96, to permit the cutter 90 to extend therethrough. Preferably a second cutter, similar to the cutter 90, together with a second pair of gages similar to gages 92 and 94 but reversely arranged, is employed for forming the groove at the opposite side of the heel. When parallel-sided grooves, such as those shown in Fig. 10, are to be made in a heel the material between the grooves may be conveniently removed by the action of a single side milling cutter, such as that shown at 98 in Fig. 11, this cutter being provided with a guard 100 at one end for protecting the adjacent outer side of the groove from injury. In using the cutter 98 the heel

is first moved past the cutter so that the material between the middle of the breast and one of the grooves is removed and thereafter the heel is turned 180° and the heel again moved past the cutter to remove the remainder of the material between the grooves.

Having described my invention, what I claim as new and desire to secure by Letters Patent of the United States is:

- 10 1. That improvement in methods of preparing the breasts of heels for the reception of paneled breast coverings which consists in forming a groove along each lateral margin of the breast of a heel to define the lateral edges of a panel, and thereafter widening the grooves in directions toward the middle of the heel breast.
- 15 2. That improvement in methods of preparing the breasts of heels for the reception of paneled breast coverings which consists in forming a groove along each lateral margin of the breast of a heel to define the lateral edges of a panel, and thereafter widening the grooves sufficiently to unite them.
- 20 3. That improvement in methods of preparing the breasts of heels for the reception of paneled breast coverings which consists in forming a groove along each lateral margin of the breast of a heel and parallel to the adjacent edge of the breast thereof to define the lateral edges of a panel, and widening the grooves by removing material adjacent to their inner sides.
- 25 4. That improvement in methods of preparing the breasts of heels for the reception of paneled breast coverings which consists in cutting a shoulder along each lateral margin of the breast of a heel to define the lateral edges of a panel, and cutting away the surface of the breast between the shoulder cuts to define the surface of the panel.
- 30 5. That improvement in methods of preparing the breasts of heels for the reception of paneled breast coverings which consists in forming a groove along each lateral margin of the breast of a heel to define the edges of a panel, widening the grooves toward the middle of the heel breast, and thereafter removing material adjacent to the inner sides of the widened grooves to determine the ultimate shape of the bottom surface of the panel.
- 35 6. That improvement in methods of preparing the breasts of heels for the reception of paneled breast coverings which consists in forming a V-shaped groove along each lateral margin of the breast of a heel to define the lateral edges of a panel, and cutting away the portions of the breast surface located between said grooves and projecting beyond a plane extending through the bottoms of said grooves.

- 40 7. That improvement in methods of preparing the breasts of heels for the reception of paneled breast coverings which con-

sists in operating progressively along the opposite lateral margins of the breast of a heel to form grooves extending heightwise of the heel breast while gaging the grooving operations from the sides of the heel to form grooves parallel to the respective lateral edges of the heel breast, and cutting away the material at the surface of the heel breast between the grooves while guarding the outer sides of the grooves against injury resulting from said cutting operation.

8. That improvement in methods of preparing the breasts of heels for the reception of paneled breast coverings which consists in moving a heel past a groove-forming tool while guiding the heel to cause the cutter to form a groove along each lateral margin of the breast surface of the heel, and thereafter presenting the heel to a tool adapted to remove material from the breast of the heel between said grooves and manipulating the heel to cause the second tool to remove said material.

9. That improvement in methods of preparing the breasts of heels for the reception of paneled breast coverings which consists in operating progressively along the opposite lateral margins of the breast of a heel to form grooves extending heightwise of the heel while gaging the depth of the grooves from the heel breast surface and while gaging the locations of the grooves widthwise of the heel breast from the sides of the heel adjacent to the respective edges of the breast face, and thereafter removing material from the surface of the heel breast between said grooves.

10. That improvement in methods of preparing the breasts of heels for the reception of paneled breast coverings which consists in forming a groove along one lateral margin of a heel, thereafter forming a similar groove along the opposite lateral margin of the heel, cutting away material at the inner side of one of said grooves to form a surface sloping from the bottom of the groove outwardly to the middle of the breast face, thereafter similarly cutting away the material adjacent to the inner side of the other groove, and leveling the angular breast surface produced by said cutting operations.

In testimony whereof I have signed my name to this specification.

JOHN T. KERSHAW.
